UNITED STATES PATENT OFFICE

STEPHEN J. RAETZ, OF LOWELL, MASSACHUSETTS

ASH PAN STRUCTURE

Application filed April 14, 1930. Serial No. 444,217.

My invention relates to railway rolling stock and consists in a novel ash pan door supporting arrangement.

It has been customary to build locomotive ash pan hoppers with grooves along the bottoms of the sides of the hoppers, in which grooves, the edges of the hopper doors were supported and guided. This type of structure is disadvantageous in that the grooves become choked with ashes and other waste material so that it becomes extremely difficult to move the doors, particularly from the open to the closed positions. To clean the grooves, it is necessary to get under the locomotive with suitable tools and dig the ashes and waste material of other character out of the grooves. In the case of the modern locomotive, the brake rigging and the spring equalizing system of the trailer truck make the ash pan door support grooves very inaccessible, and the job of cleaning those grooves an extremely difficult one.

The main object of my invention is to provide a door support which eliminates or reduces the accumulation of waste material on the support so as to interfere with the operation of the door.

Another object of my invention is to provide an anti-friction means on the door support to facilitate the movement of the door.

In the accompanying drawings which illustrate a selected embodiment of my invention—

Figure 1 is a side view of a locomotive ash pan structure equipped with my novel door supports, and associated structure.

Figure 2 is a vertical section taken on the longitudinal center line of one of the hoppers of the structure shown in Figure 1.

Figure 3 is a half bottom view of one of the hoppers shown in Figure 1.

Figure 4 is a vertical transverse section taken on the line 4—4 of Figure 1.

Figure 5 is a vertical transverse section taken on the line 5—5 of Figure 1.

In Figure 1, two hoppers A and B are shown to be duplicates of each other in every respect except that the brackets to which the door opening mechanism is attached are mounted on adjacent ends of the doors.

At the bottom of the side 1 of each hopper, a door guide and support is formed by the vertically extending portion 2, the upper substantially horizontal ledge 3 and spaced members 4. The upper surfaces of the members 4 have rounded edges and the front and rear edges of the door are also rounded as indicated at 13 so that the edge of the door will not tend to catch upon members 4 as the door is moved over them. The flange 5 of the door 6 is supported and guided between ledge 3 and members 4.

In the center of the guide and support structure, I connect two of the spaced members 4 with a web 10 and in the pocket formed thereby I mount a roller 8 by means of the bolt 9 held in place by nut 14. Roller 8 extends a little above the level of the plane of the top surfaces of the members 4 and web 10 and always supports the door, thus greatly facilitating the movement of the door.

A bushing 11 is pressed into the roller 8. The roller 8 has bosses 12 on its sides to space its periphery from the adjacent ash pan parts.

Between the spaced member 4 there are open spaces 18 through which any ashes or other waste material that may have collected on the door support will be pushed as the door is moved.

On the brackets 19 and 20 mounted on the adjacent ends of the doors of hoppers A and B respectively is mounted means 21, 22, 23, 24 and 25 by which the doors are opened simultaneously.

It will be understood that the door guide and support structures described are duplicated on opposite sides of the hoppers.

The provision of the openings 18, even though the roller feature is not included, solves the problem of the collection of ashes on the support and I contemplate that a construction not including the roller would be within the spirit of my invention. Also, I contemplate the mounting of the roller by means of a stud bolt and eliminating the web 10 where clearance is so slight that there is not sufficient room for the web.

Obviously, other details of the construction may be varied without departing from the

spirit of my invention and I contemplate the exclusive use of such modifications as come within the scope of my claim.

I claim:

- 5 In a railway locomotive ash pan hopper having side walls with a discharge opening between them, a downwardly extending member at the bottom of each of said side walls and spaced from the edge of said opening,
- 10 door support elements comprising lugs disposed at intervals along said member and projecting toward said opening with spaces between them for the escape of ashes, a web connecting the inner ends of two adjacent
- 15 elements and spaced from said member, a roller journaled in said member and web, and a door supported by said roller and at least one of said lugs.

In testimony whereof I hereunto affix my signature this 29th day of March, 1930.

STEPHEN J. RAETZ.
